Primary Examiner — Jack Reickel*Assistant Examiner* — Salamah Jordan(74) *Attorney, Agent, or Firm* — Banner & Witcoff, Ltd.(57) **CLAIM**

The ornamental design for a handle for a resistance band as shown and described.

DESCRIPTION

FIG. 1 is a top, front, right perspective view of a handle for a resistance band showing my new design;

FIG. 2 is a top, rear, left perspective view thereof;

FIG. 3 is a right side view thereof;

FIG. 4 is a left side view thereof;

FIG. 5 is a front view thereof;

FIG. 6 is a rear view thereof;

FIG. 7 is a top view thereof; and,

FIG. 8 is a bottom view thereof.

The even-length broken lines depicting the remainder of the article show portions of the article that from no part of the claimed design.
